CHRISTOPHER BECKER, OF NEW ROCHELLE, NEW YORK.

WEIGHING-SCALE.

SPECIFICATION forming part of Letters Patent No. 313,468, dated March 10, 1885.

Application filed September 30, 1884. (No model.)

To all whom it may concern:

Be it known that I, CHRISTOPHER BECKER, a citizen of the United States, residing at New Rochelle, in the State of New York, have 5 invented a new and useful Improvement in Scales, of which the following is a specification.

In the accompanying drawings, Figure I represents a side view of a scale, partly in 10 section, with my improvement attached. Fig. II is a cross-section at the center line, A, Fig. I. Fig. III is a top view of the beam D at the line B, Fig. I. Fig. IV is a cross-section at line B, Fig. I.

15 Similar letters represent similar parts in all the figures.

Upon a suitable frame, C, a stand, E, is attached, supporting the balance-beam F and the usual knife-edges, a, and at the ends of said 20 beam the scale-pans G are supported in a similar manner, only one of which is shown in the drawings.

Below the balance-beam F, a beam, D, is arranged, resting upon the top of the frame made with suitable slots or openings, D', Fig. III,) through which the rods and 25 h, which support the scale-pans G, can This beam D extends some distance of the scale-pans G.

30 The lower part of the frame C, levers H arranged some distance below the C, turning upon fixed centers b b C. The outer ends of these levers and of the beam D are connected together by rods K.

The center of the beam D is attached to a 35 rod, L, guided in the frame C, to the lower end of which a rod, N, is attached, operated by a crank-pin, w, fast to a suitable disk at the end of the crank-shaft M.

At the center of the beam D, a suitable 40 frame, P, is attached, extending upward to within a short distance of the knife-edges a on the balance-beam F.

45 On each side of the openings D' of the beam D, bearings m m are attached, for the knife-edges n n, attached on the outside of the strap h, whenever the beam D is moved upward.

50 In the levers H H, screw-buttons R are arranged directly under the center of the scale-pans G, the top of which may be covered by a soft material.

Whenever the scales are to be used, and

any weight is to be placed upon the scale-pans G, or some weight to be taken off, the crank-shaft M will be turned by means of a knob or other suitable attachment at its outer end, so as to move its crank-pin w upward, when, through the connecting-rod N 60 and rod L, the beam D will be moved upward. The bearings m m will then come first in contact with the knife-edges n n at the sides of the straps h, lifting thereby the scale-pans off from the ends of the balance-beam F. At the same time the levers H H will be moved upward on account of their connection with the beam D, through the rods K, whereby the screw-buttons R will come against the under side of the scale-pans 70 G, supporting thereby the bottom of the scale-pans, and thus prevent any vibration.

A further upward motion of the beam D brings the frame P in contact with the knife-edges a a of the balance-beam F, and lifts 75 the same off its bearings. The scale-pans G are therefore by this arrangement supported on top and bottom and clear of the balance-beam F, and any weight may be placed upon the scale-pans or taken off from the 80 same without producing any vibration at the scale-pans and without producing any detrimental effect upon the knife-edges at the ends of the balance-beam F, or upon the 85 central knife-edges, a, of said beam, this beam F and the scale-pans G being during that time supported independent of each other.

The turning of the crank-shaft M, so as to move its crank-pin w downward, will bring 90 all parts gradually into their normal position, and then leaves the balance-beam F and scale-pans G perfectly free ready to weigh any article placed in the scale-pans in the usual manner.

What I claim as my invention, and desire to 95 secure by Letters Patent, is—

In combination with a balance-beam, F, and scale-pans G, and projections n n at the sides of the suspending-strap h, the beam D, with central frame, P, bearings m m, rods K K, levers H H, turning on fixed centers b b and screw-buttons R R, crank-shaft M, connecting-rod N, and rod L, substantially in the manner and for the purpose described.

CHRISTOPHER BECKER.
